US0D1110777S

(12) **United States Design Patent** (10) **Patent No.:** **US D1,110,777 S**
(45) **Date of Patent:** **** Feb. 3, 2026**

(54) **STAND FOR A BAG OR COMPUTER**

(71) Applicant: **Nupur, LLC**, Baltimore, MD (US)

(72) Inventors: **Nupur Parekh Flynn**, Baltimore, MD (US); **Jennifer Ann Ewing**, Baltimore, MD (US); **Jeremy Asher Higgins**, Baltimore, MD (US); **Douglas Pemberton**, Baltimore, MD (US); **Joshua Barnes**, Kansas City, OK (US)

(73) Assignee: **NUPUR, LLC**, Baltimore, MD (US)

(**) Term: **15 Years**

(21) Appl. No.: **29/879,059**

(22) Filed: **Jun. 30, 2023**

Related U.S. Application Data

(62) Division of application No. 29/776,462, filed on Mar. 30, 2021, now Pat. No. Des. 996,069.

(57) **CLAIM**

An ornamental design for a stand for a bag or computer, as shown and described.

DESCRIPTION

FIG. 1 is a top perspective view of the stand for a bag or computer showing our new design;
FIG. 2 is a right side view thereof;
FIG. 3 is a left side view thereof;
FIG. 4 is a front view thereof;
FIG. 5 is a back view thereof;
FIG. 6 is a top view thereof;
FIG. 7 is a bottom view thereof; and,
FIG. 8 is a bottom perspective view thereof.
The broken lines in the drawings represent unclaimed subject matter and form no part of the claim.

1 Claim, 7 Drawing Sheets
